TURNS COUNTER

Hugh O. Brown, Fullerton, Calif., assignor to Beckman Instruments, Inc., a corporation of California

Filed Oct. 18, 1965, Ser. No. 87,535

Term of patent 14 years

(Cl. D52—6)

Fig. 1

Fig. 3

Fig. 2

FIG. 1 is a perspective view of a turns counter embodying my new design.

FIG. 2 is a side elevation of the right side of the turns counter as shown in FIG. 1.

FIG. 3 is a rear view of the turns counter of FIG. 1. The left side of the turns counter is substantially plain.

I claim:

The ornamental design for a turns counter, substantially as shown and described.
